(57) **CLAIM**

The ornamental design for a box with surface ornamentation, as shown and described.

DESCRIPTION

FIG. 1 is a front perspective view of a box with surface ornamentation illustrating an embodiment of my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view of another embodiment of the box with surface ornamentation;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a front perspective view of another embodiment of the box with surface ornamentation;

FIG. 16 is a front view thereof;

FIG. 17 is a rear view thereof;

FIG. 18 is a left side view thereof;

FIG. 19 is a right side view thereof;

FIG. 20 is a top view thereof;

FIG. 21 is a bottom view thereof;

FIG. 22 is a front perspective view of another embodiment of the box with surface ornamentation;

(Continued)

FIG. 23 is a front view thereof;
 FIG. 24 is a rear view thereof;
 FIG. 25 is a left side view thereof;
 FIG. 26 is a right side view thereof;
 FIG. 27 is a top view thereof;
 FIG. 28 is a bottom view thereof;
 FIG. 29 is a front perspective view of another embodiment of the box with surface ornamentation;
 FIG. 30 is a front view thereof;
 FIG. 31 is a rear view thereof;
 FIG. 32 is a left side view thereof;
 FIG. 33 is a right side view thereof;
 FIG. 34 is a top view thereof;
 FIG. 35 is a bottom view thereof;
 FIG. 36 is a front perspective view of a box with surface ornamentation illustrating an embodiment of my new design;
 FIG. 37 is a front view thereof;
 FIG. 38 is a rear view thereof;
 FIG. 39 is a left side view thereof;
 FIG. 40 is a right side view thereof;
 FIG. 41 is a top view thereof;
 FIG. 42 is a bottom view thereof;
 FIG. 43 is a front perspective view of another embodiment of the box with surface ornamentation;
 FIG. 44 is a front view thereof;
 FIG. 45 is a rear view thereof;
 FIG. 46 is a left side view thereof;
 FIG. 47 is a right side view thereof;
 FIG. 48 is a top view thereof;
 FIG. 49 is a bottom view thereof;
 FIG. 50 is a front perspective view of another embodiment of the box with surface ornamentation;
 FIG. 51 is a front view thereof;
 FIG. 52 is a rear view thereof;
 FIG. 53 is a left side view thereof;
 FIG. 54 is a right side view thereof;
 FIG. 55 is a top view thereof; and,
 FIG. 56 is a bottom view thereof.
 The broken lines in the drawings are included for the purpose of illustrating environmental structure and form no part of the claimed design. In the drawings, the stippling indicates color contrast.
